UNITED STATES PATENT OFFICE.

JOSEPH SPADAFORA, OF CAMBRIDGE, MASSACHUSETTS, ASSIGNOR TO COMBO MANUFACTURING COMPANY, A CORPORATION OF MASSACHUSETTS.

COMBINATION LOCK.

Application filed June 8, 1921. Serial No. 476,079.

To all whom it may concern:

Be it known that I, JOSEPH SPADAFORA, a citizen of the United States, and resident of Cambridge, county of Middlesex, State of Massachusetts, have invented an Improvement in Combination Locks, of which the following description, in connection with the accompanying drawing, is a specification, like characters on the drawing representing like parts.

This invention relates to combination locks and has for one of its objects to provide a combination lock which is adapted for a variety of purposes but is specially applicable for use as an automobile lock in locking and unlocking the steering wheel of an automobile.

Another object of the invention is to provide an improved combination lock which is constructed so that the combination can be readily changed.

Other objects of the invention are to improve generally locks of this type all as will be more fully hereinafter set forth.

25 My improved lock comprises a shiftable member to be locked, a plurality of tumbler elements for locking said members from movement but which when lined up release the member, a single setting member for 30 lining up the tumblers and manually-controlled means to limit positively the setting movement of the setting member.

The lock is adapted for a variety of purposes but as stated above it is specially advantageous when used as an automobile steering wheel lock and in order to give an understanding of the invention I have chosen to illustrate it in the drawings as it would be employed in connection with the steering wheel of an automobile.

In the drawings, Fig. 1 is a sectional view through a steering wheel having my improved lock.

Fig. 2 is a plan view of the steering wheel hub with the "combination" part of the lock removed.

Fig. 3 is a plan view of the cam for operating the locking pin.

Fig. 4 is a sectional view through the hub 50 showing the collar 3.

Fig. 5 is a sectional view through the cam on the line 5-5, Fig. 3.

Fig. 6 is a top plan view of the steering wheel head showing the dial which forms the guide for manipulating the lock.

Fig. 7 is a section through the hub of the steering wheel and the lock taken on the angular line 7-7, Fig. 2 and showing the steering wheel locked in its "wild" condition.

Fig. 8 is a similar view showing the steering wheel connected to the steering shaft.

Fig. 9 is an enlarged top plan view of the casing supporting notched rings, said rings being shown in relative position they occupy when the lock is set.

Fig. 10 is a similar view showing rings lined up to release the lock.

Fig. 11 is a bottom plan view of the setting member.

Fig. 12 is a perspective view of the actuating cam. 70

Fig. 13 is a perspective view of the locking pin.

Fig. 14 is a perspective view of one of the notched rings.

Fig. 15. is a sectional view showing the manner in which the setting member operates the rings.

Fig. 16 is a fragmentary sectional view showing the manner in which the setting 80 member actuates the notched rings.

In the drawings 1 indicates a steering wheel of an automobile and 2 is the steering shaft which extends down through the steering post and to which the usual steering arm is connected. In my improved lock the steering wheel is normally free from the steering shaft 2, in which case the steering wheel is inoperative so far as steering the automobile is concerned; but the steering wheel can be operatively connected to the steering shaft 2, in which case the steering wheel is operative as usual for steering the automobile. This connecting of the steering wheel to and disconnecting it from the steer-

wheel 10 and disconnecting it from the steering shaft 2 is accomplished by means of a collar 3 which is fast on the shaft 2 and is provided with a plurality of recesses 4, and a connecting pin 5 which is carried by the hub 6 of the steering wheel and is adapted to be entered in one of the recesses 4 or withdrawn therefrom. This connecting pin 5 is shown as extending through the hub 6 and as being acted upon by a spring 8 which tends to raise the connecting pin and thus withdraw it from the recess 4, said pin having a head 7 against which the spring acts.

When the pin 5 is depressed into the position shown in Fig. 8 the lower end thereof 110

enters one of the recesses 4 and thus the steering wheel 1 becomes rigidly connected to the shaft 2 through the collar 3, and so long as the connecting pin 5 retains this position the steering wheel is operative for steering the automobile in the usual manner. If, however, the connecting pin is raised into the position shown in Fig. 7 and thus withdrawn from the recess 4, the steering wheel will be disconnected from the steering shaft and can rotate freely thereabout without giving rotation to the steering shaft. In this condition the steering wheel is "wild" as it is termed, and is inoperative for steering the automobile.

The steering wheel hub is shown as having a depending flange 9 which encircles the collar 3, said collar thus forming a bearing for the steering wheel. The steering wheel hub is prevented from being withdrawn from the collar by means of a screw 10 which passes through the flange 9 and is screw-threaded into a nut 11 that is received in a peripheral groove 12 formed in the collar 3. In order to make it impossible for anyone to remove the screw 10 when the steering wheel is in its free or "wild" condition, I have made the groove 12 of sufficient depth to intersect the recesses 4 and I have made the nut 11 with the flat portion 13 on its inner end, said flat portion occupying the part of the groove 12 which intersects the recesses 4. When the connecting pin 5 is in its operative depressed position shown in Fig. 8 the lower end of the pin will engage the flat portion 13 of the nut 11 and thus prevent said nut from turning, and so long as the nut is thus held from turning the screw 10 may be unscrewed and removed. When, however, the connecting pin 5 is in its raised position shown in Fig. 7 then the nut 11 is free to rotate and it will turn with the screw 10 thus making it impossible to remove the screw.

The connecting pin 5 is moved from its lowered position shown in Fig. 7 to its raised position shown in Fig. 8 by means of the spring 8. It is given its reverse movement by means of an actuating cam 14 which is mounted for rotation about the axis of the steering wheel. This cam 14 is shown as carried by a ring 15 and it may be either integral with the ring or a separate part inserted into the ring. This ring is shown having a flange 16 which sets within a curb 17 formed on the steering wheel and hub, said hub centering the ring and holding it in proper position.

The connecting pin 5 is shown in dotted lines in the position relative to the cam corresponding to Fig. 7, when the ring 15 is turned clockwise, Fig. 3, the cam 14 will act on the pin 5 and depress the latter into locking engagement with the collar 3.

The operation of connecting the steering

wheel to or disconnecting it from the shaft 2 therefore involves the partial rotation of the ring 15 and cam 14.

A combination lock device is employed for locking the ring 15 either in the relative position shown in Fig. 7 or that shown in Fig. 8, so that when the cam ring is locked in either position it can only be unlocked by one knowing the combination.

Such combination lock device comprises in its construction a locking member 18 in the form of a pin situated axially of the shaft 2 and movable axially in a sleeve 19 that is rigidly connected to the hub 6 by means of a screw 20 screwed into the lower end of the sleeve and having a head 21 overlying the under side of the hub 6, and by means further of a projection 22 carried by the hub and entering a slot 23 formed in the sleeve.

The locking member 18 is acted on by a spring 24 which normally moves it downwardly and said member is provided with a laterally extending locking arm 25 which rides on the upper face of the cam member 14. This upper face is formed with the two notches 26 and 27 between which is the raised portion 28. When the arm 25 occupies either notch 26 or 27 and is held from vertical movement, the cam 14 will be locked from turning movement. These notches 26 and 27 are so disposed relative to each other that the locking arm 25 will occupy one notch when the ring 15 is in the relative position shown in Fig. 7, and will occupy the other notch when said ring is in the relative position shown in Fig. 8.

Therefore as long as the locking arm is held in either notch 26 or 27 the locking cam will be locked from rotation and the steering wheel will either be locked to the shaft or will be locked in its "wild" condition.

The upward movement of the locking member 18 is controlled by a plurality of tumblers herein shown in the form of notched or slotted rings which are arranged so that when they are set with their notches or slots out of alignment the locking arm 25 is held depressed, but when they are set so that their notches or slots are in alignment the locking arm may be raised through the aligned notches or slots thus permitting the cam 15 to be turned.

In the present embodiment of my invention there are three of these notched or slotted rings indicated at 29, 30 and 31 respectively. These rings are concentric with each other and with the axis of the steering wheel and are mounted for independent rotation in a head 32 which is superposed on the ring 15, said head having a hub 33 which extends down through the cam ring and by which the head is properly centered. Said head is provided with an

nular grooves 34 to receive the rings 29, 30 and 31. Each ring is provided with a notch or space 35 of a width to receive the locking arm 25. These rings are situated above the locking arm 25 when the latter is depressed and so long as the rings are arranged with their notches or slots 35 out of alignment as shown in Figs. 7 and 9 they will hold the locking arm 25 depressed into one or the other notches 26 or 27. When, however, the rings are adjusted relative to each other to bring their notches or slots into alignment as shown in Fig. 10 and in a position over the locking arm 25, then said arm is free to be raised thereby permitting the cam ring 15 to be turned.

Situated above the head 32 is a setting member 36 which is rotatable about the sleeve 19 and by which the notched rings 20 may be positioned. Each notched or slotted ring is provided with a projection 37 rising therefrom and the setting member is provided with projections 38 depending therefrom which are situated to engage the projections 37 of the notched or slotted rings. These projections 37 and 38 are so disposed relative to each other that a turning of the setting member 36 in one direction or the other and through the proper angles will line up the 25 rings into the position shown in Fig. 10. The degree and direction of the turning movement of the setting member to bring each ring into the "lined up" position depends, of course, upon the relative position 30 of the projections 37 and 38.

To assist the operator in setting the combination the head 32 is provided with stop pins 39 which are radially arranged and which project beyond said head, each stop 40 pin being acted upon by a spring 40 which yieldingly holds it in its outward position. Each stop pin 39 is provided with a projection 41 which normally lies against the inner wall of the curb 42 of the head. The 45 setting member 36 is provided with a flange 43 concentric with but spaced from the curb 42 and which is provided with a stop projection 44. This projection 44 is situated inside of the projections 41 when they are 50 against the curb 42 so that when the stop pins 39 are in their normal position the setting member is free to be turned. If, however, any stop pin 39 is pressed inwardly the projection 41 thereon will be 55 carried into the path of movement of the projection 44 thus limiting the turning movement of the setting member.

By manipulating the stop pins 39 in a pre-determined order and turning the setting member 36 in one direction or the other after pressing in each stop pin until the projection 44 is brought up against a projection 41, the notched or slotted rings 29, 30 and 31 will be positioned with their 60 notches or slots in line with each other and

in line with the locking member 25. When this condition exists then the cam ring 15 can be turned thereby either locking the steering wheel to the steering shaft 2 or freeing it therefrom.

After the cam ring has been turned then the lock can be upset by simply turning the setting member 36 in one direction or the other thereby placing the notched or slotted rings with their notches or slots out of alignment.

The sleeve 19 is herein shown as closed at its upper end at 45 and said upper end may be provided with numbers 46 as shown in Fig. 6, there being one number for each 80 of the pins 39. This graduation or numbering 46 provides a guide to assist the operator in manipulating the proper pins 39 to effect a release of the lock.

The projections 37 and 38 may be arranged so that in order to release the lock certain pre-determined pins 39 must be manipulated in certain pre-determined order.

I have provided a construction herein by which it is easy to change the combination 90 and I accomplish this by making the projections 38 adjustable in the setting member 36. These projections are shown in the form of screws which are screwed into screw-threaded apertures 47 formed in the 95 setting member and this construction makes it easy to shift the position of the projections thereby changing the combination.

In the construction shown the body of the steering wheel 1 is pivoted to the hub 6 100 so that said steering wheel may be swung up into a vertical position. This pivotal connection is shown at 51 and to lock the steering wheel in its operative position the latter is provided with a recess 53 adapted to receive a spring-pressed locking pin 52 carried by the boss 54 formed on the steering wheel. This locking pin is acted on by the spring 53 which normally holds it in operative position. The locking pin can readily 105 be withdrawn to permit the steering wheel to be swung into its vertical position. The claims in this application are directed to the combination lock regardless of the use to which it is put. In my co-pending application Serial No. 546,223, filed March 24, 1922, I have claimed the steering wheel construction.

I claim:

1. In a lock, the combination with a shiftable member to be locked having a laterally-projecting arm, of a plurality of concentric slotted rings adapted to co-operate with said arm to lock the member from movement, a setting member turnable about the axis of the rings for shifting the latter into a position to bring the slots thereof in alignment, and depressible stop pins adapted when depressed to limit the shifting movement of the setting member.

- 4
2. In a lock, the combination with a head, of a member to be locked having a laterally-projecting arm, a plurality of concentric slotted rings carried by said head and co-operating with said arm to lock the member from movement, a setting member turnable on said head about the axis of said rings and arranged to set the latter to bring the slots thereof into alignment, and a plurality of radially-arranged depressible stop pins carried by the head for limiting the turning movement of the setting member.
3. In a lock, the combination with a member to be actuated, of a cam element for actuating said member, a locking member for locking the cam element from movement, said locking member having a laterally-extending arm, a plurality of concentric slotted rings co-operating with said arm to lock the locking member from movement, a rotatable setting member to shift the slotted rings thereby to bring their slots into alignment with the arm thereby unlocking the locking member, and a plurality of depressible stop pins to limit the turning movement of the setting member.
4. In a lock, the combination with a head, of a member to be actuated, a rotatable cam for actuating said member, a locking member having a laterally-extending arm co-operating with said cam to lock it from movement, a plurality of concentric slotted rings co-operating with said arm to hold the locking member in locking position, a setting member rotatable about the axis of said ring for shifting the latter into position to bring their notches into alignment with said arm thereby releasing the locking member from locking engagement with the cam, and manually-controlled means to limit the turning movement of the setting member.
5. In a lock, the combination with a head, of a member to be actuated, a rotatable cam for actuating said member a locking member having a laterally-extending arm co-operating with said cam to lock it from movement, a plurality of concentric slotted rings co-operating with said arm to hold the locking member in locking position, a setting member rotatable about the axis of said ring for shifting the latter into position to bring their notches into alignment with said arm thereby releasing the locking member from locking engagement with the cam, and a plurality of depressible stop pins limiting the turning movement of the setting member.
6. In a lock, the combination with a head, of a member to be actuated, a rotatable cam for actuating said member, a locking member having a laterally-extending arm co-operating with said cam to lock it from
- movement, a plurality of concentric slotted rings co-operating with said arm to hold the locking member in locking position, a setting member rotatable about the axis of said ring for shifting the latter into position to bring their notches into alignment with said arm thereby releasing the locking member from locking engagement with the cam, a plurality of spring-pressed depressible stop pins carried by said head and each adapted when depressed to limit the turning movement of the setting member.
7. In a lock, the combination with a shiftable member to be locked, of a plurality of concentric slotted rings for locking said member from movement, a setting member independent from the shiftable member and turnable about the axis of said rings for shifting the latter into a position to release the member to be locked, and manually-controlled means to limit the shifting movement of the setting member.
8. In a lock, the combination with a head, of a plurality of concentric slotted rings carried by said head, a member to be locked situated axially of the head, and adapted to be locked by said rings, a setting member co-axial with the rings for setting the latter to line them up, and a plurality of radially arranged stop pins carried by said head for limiting the turning movement of the setting member.
9. In a lock, the combination with a shiftable member to be locked, of a plurality of concentric slotted rings for locking said member from movement, a setting member turnable about the axis of said rings for shifting the latter into a position to release the member to be locked, and manually-controlled means to limit positively the shifting movement of the setting member.
10. In a lock, the combination with a shiftable member to be locked, of a plurality of tumbler elements for locking said member from movement but which when lined up release said member, a single setting member for lining up the tumblers, and manually-controlled means to limit positively the setting movement of the setting member.
11. In a lock, the combination with a shiftable member to be locked, of a plurality of tumbler elements for locking said member from movement but which when lined up release said member, a single setting member for lining up the tumblers, and a plurality of depressible stop pins for limiting positively the movement of the setting member.

In testimony whereof, I have signed my name to this specification.

JOSEPH SPADAFORA.
